UNITED STATES PATENT OFFICE.

JOHN A. JOHNSON AND CARL M. HEDMAN, OF CHICAGO, ILLINOIS, ASSIGNORS TO THE RANSOM & RANDOLPH COMPANY, OF TOLEDO, OHIO, A CORPORATION OF OHIO.

PNEUMATIC POTENTIAL-PRODUCING MEANS.

1,096,305.

Specification of Letters Patent.

Patented May 12, 1914.

Original application filed April 25, 1908, Serial No. 429,142. Divided and this application filed June 24, 1911. Serial No. 635,110.

To all whom it may concern:

Be it known that we, JOHN A. JOHNSON and CARL M. HEDMAN, both citizens of the United States, residing at Chicago, in the county of Cook and State of Illinois, have invented certain new and useful Improvements in Pneumatic Potential-Producing Means, of which the following is a full, clear, concise, and exact description, reference being had to the accompanying drawings, forming a part of this specification.

Our invention relates to pneumatic potential producing apparatus and contemplates an improved arrangement and improved construction of the parts thereof.

This application is divisional from our copending application, Serial No. 429,142, filed April 25, 1908, Patent No. 999,794, dated Aug. 8, 1911.

As pointed out in our copending application referred to, the potential producing apparatus of our invention is particularly adapted for use as part of a so-called "inlay casting" equipment, such as is used by present-day dentists in the making of fillings for teeth.

It will appear, however, that our invention may have other advantageous uses and we contemplate its varied application in this respect, although, as will be seen, a peculiar relationship exists between the potential producing apparatus and the flask arrangement to form a simple, useful, and unique casting outfit for the purpose pointed out.

One of the main features of our invention is the disposition of the pump which is carried by the pressure or vacuum tank to form a unitary outfit. The tank is substantially cylindrical or barrel-shaped, and the pump extends axially through the tank and is secured therein, only the handle part being at the outside.

Another feature of our invention resides in the valve construction and, in this connection, it might be stated that the potential producing means of our invention may be used either as a vacuum pump or as a pressure pump, the change being made by merely reversing the valve and the pump piston.

In the specific description which follows,

as an example of our invention, we explain our apparatus in the light of a vacuum pump and at the same time set forth the effective combination between it and the inlay casting apparatus.

In the accompanying drawings, Figure 1 is a front elevational view of our device; Fig. 2 is a side elevational view thereof; Fig. 3 is a longitudinal sectional view taken on the plane of the line 3-3 of Fig. 1 and looking in the direction indicated by the arrows; Fig. 4 is a fragmentary longitudinal sectional view of one end of the pump, showing the valve mechanism on a larger scale; Fig. 5 is a cross-sectional view taken on the plane of the line 5-5 of Fig. 4 and looking in the direction indicated by the arrows; and Fig. 6 is an enlarged face view of the valve disk which we employ.

The pressure or vacuum tank 1 may be cylindrical or more or less barrel-shaped, as shown, and is provided with a plurality of feet 2-2 by means of which it may be rigidly secured to a suitable support. The cylindrical pump 3 which we employ comprises the pump barrel 3 having the guide head 4 for the piston rod 5, and at its other end the barrel or cylinder 3 is closed by the valve frame 6. The outer end of the piston rod 5, which rides in an axial opening in the guide head 4, terminates in a handle or knob 7, while at the other end there is secured thereto the plunger 8, of leather or similar material, between the washers 9 and 10 held in place by nuts 11 and 12.

The valve frame 6 has the inner bore section 13, the intermediate bore section 14, of larger diameter, and the outer threaded bore section 15 which is engaged by a nut 16 having the axial passageway 17 therethrough. Within the bore part or compartment 14, the valve disk 18, whose form is best shown in Fig. 6, is disposed. This disk is made by cutting semi-circular notches in the edge of the circular disk to leave the bypasses 19, 19.

Brazed to the front end of the pump barrel is a sleeve 23 having a threaded portion 100 for engaging in the threaded opening 25 through the front head of the tank, the outer portion of the sleeve being polygonal so that a wrench may be applied. A washer

26, of lead or other suitable material, is interposed between the head of the sleeve 23 and the head of the tank so that an airtight fit will result. The rear end of the pump 5 extends into and is supported in a niche 27 in the rear head of the tank. The entire pump structure can readily be unscrewed bodily from the tank. The guide head 4 is held in the barrel or cylinder 3 by means 10 of a screw 28 and by removing this screw the head, the stem, and the plunger may be easily removed. By removing the nut 16 the valve member 18 may be removed, and it will thus be seen that the various parts 15 are all of convenient access and of simple and economical construction.

When the pump rod is pulled out air is withdrawn from the tank into the pump barrel, the valve disk during this outward 20 movement of the plunger resting against the shoulder or seat 19, at the left end of the valve compartment 14, and the air can flow from the tank through the by-passes 19 and into the pump barrel, the passageway 25 13 being large enough for this purpose. When the plunger comes to rest or is moved rearwardly, the valve disk is thrown against the inner face of the nut 16, this face being within the area of the by-passes 19, so that 30 the passage 17 will be closed, and the reduced pressure in the tank is thus maintained. The air which was drawn into the barrel upon the outward movement of the plunger will pass by the flexible plunger edges when the plunger is moved inwardly. Upon outward movement of the plunger the air in front thereof escapes to the outside 35 atmosphere through the passageways 20, 20, through the head 4. The pressure in the 40 tank may be indicated by a pressure gage 21 suitably mounted thereon and pneumatically connected therewith. As an additional feature, a buffer spring 22 encircles the pump rod and acts as a cushion for the 45 plunger when the latter reaches the outer end of the barrel. It will be seen from the above description that we have produced a unitary structure by mounting the flask or casting device on the tank and by having 50 the pump rigidly attached to the tank—that is, rigid with respect to the tank in the sense that it is not separate from the tank but is carried with it.

We shall now proceed to describe the 55 structure wherein the pressure potential producing means forms a part of a vacuum casting system for making dental inlays.

A T-member 29 is screwed into the top of the front end of the tank and at the ends of 60 the cross piece carries the valve members 30 and 31 to which are secured the elbow members 32 and 33, respectively. Mounted on the elbow 32 is a cup member 34 and mounted upon the elbow 33 is a cup member 65 35. Each cup member has a vertical

flange 36 and a planed horizontal annular section 37, forming a seat for a flask frame 38, whose lower end is also planed to form an airtight joint with the cup surface 37. The inner section of the cup base is provided 70 with grooves 39 which connect with the passageway 41 leading through the cup member and through the various connecting members to the tank when the corresponding valve is open.

In practice, a wax pattern of the filling to be made is suspended in the flask and the investment compound, such as plaster Paris, is poured about the pattern. When the compound has dried sufficiently and hardened, the flask is placed on its cup and heated to cause absorption of the wax, thus leaving a cavity. Gold or other suitable inlaying material is then fed to the cavity in a liquid state, the corresponding valve being open 85 so as to connect the cup with the low pressure. The melted material is drawn in by suction and is forced into the various parts of the cavity, however intricate, and a duplicate of the wax pattern is formed. Then 90 the valve may be closed and the flask cooled and the mold is then broken up so that the filling may be extracted.

In dental work, many other appliances are used during work on a patient—such appliances as a carburetor, for instance, for supplying gas. Devices of this kind are usually small and easily misplaced and our tank body would form a very efficient support for devices of this kind. In Fig. 1 we 100 show a carburetor C supported from one side of the tank.

We claim as new and desire to secure by Letters Patent:

1. In combination, a portable tank, a 105 pump barrel rigidly connected to said tank and extending through the interior of said tank, valve controlled communication between said tank and said barrel, a piston arranged to reciprocate in said barrel, and a casting device rigidly secured to the top of said tank, the tank, the pump, and the casting device being thus rigidly carried together as a unitary structure.

2. In combination, a portable tank, a complete pump mounted in said tank, said pump serving to exhaust the air from said tank, and a casting device rigidly secured to said tank and extending outwardly therefrom, the tank, the pump, and the casting device 120 being thus carried together as a unitary structure.

3. In combination, a portable tank, a pump barrel mounted in said tank and rigidly secured thereto, valve controlled 125 communication between said tank and said barrel, a piston arranged to reciprocate in said barrel, and a flask rigidly mounted upon a pipe secured to said tank, the interior of said flask communicating with the 130

interior of said tank, and said tank, pump, and flask being thus carried together as a unitary structure.

4. In combination, a portable tank, a complete pump rigidly attached to said tank, said pump having pneumatic connection with said tank, and a casting device mounted with said tank and having pneumatic connection therewith, the tank, the

pump, and the casting device being thus carried together as a unitary structure.

In witness whereof, we hereunto subscribe our names this 21st day of June, 1911.

JOHN A. JOHNSON.
CARL M. HEDMAN.
